CLAIM

The ornamental design for a nesting canning jar, as shown and described.

DESCRIPTION

FIG. 1 is a front perspective view of a nesting canning jar;

FIG. 2 is a front elevation view thereof;

FIG. 3 is a rear elevation view thereof;

FIG. 4 is left side elevation view thereof;

FIG. 5 is a right side elevation view thereof;

FIG. 6 is a top plan view; and,

FIG. 7 is a bottom plan view thereof.

The broken lines in the drawings depict portions of the nesting canning jar which form no part of the claimed design.
